UNITED STATES PATENT OFFICE.

JEFFERSON TREEN, OF NEW YORK, N. Y., ASSIGNOR TO MANHATTAN HIGH POWERED MOTOR COMPANY, OF NEW YORK, N. Y., A CORPORATION OF NEW YORK.

INTERNAL-COMBUSTION MOTOR.

No. 844,836.

Specification of Letters Patent.

Patented Feb. 19, 1907.

Application filed September 1, 1905. Serial No. 276,710.

To all whom it may concern:

Be it known that I, JEFFERSON TREEN, a citizen of the United States of America, and a resident of the borough of Manhattan, in the city, county, and State of New York, have invented certain new and useful Improvements in Internal-Combustion Motors, of which the following is a specification.

This invention relates to internal-combustion engines; and my improvements are directed to that type of engine wherein the cylinder has two opposed pistons with an intermediate combustion-chamber.

The objects attained by my novel construction and arrangement are increased power for given cylinder capacity, absence of sidereal friction between pistons and cylinder, diminution of vibration in operation, and reduction in space occupied.

In the drawings accompanying this application I have illustrated my invention as applied to a two-cylinder engine and also to a four-cylinder engine, it being obvious that my improvements are also applicable to a single cylinder or to an engine composed of a larger number of cylinders.

Figure 1 is a front sectional elevation of a two-cylinder engine embodying my improvements. Fig. 1^a is a like sectional view carried through the transmission mechanism. Fig. 2 is a side sectional elevation thereof. Fig. 2^a is a top plan view taken below the top of the crank-case. Fig. 3 is a side elevation, partly in section. Fig. 4 is a front sectional view of a four-cylinder engine. Fig. 5 is a side section thereof, and Fig. 6 is a sectional plan view taken below the top of the crank-case.

Referring first to Figs. 1 to 3, inclusive, the letters A B indicate, respectively, two vertical cylinders placed side by side, each containing pistons, as a' b', whose opposed surfaces may be concaved. The pistons in each cylinder are adapted to approach and retreat from each other in their reciprocating action, and they are provided, respectively, with the piston-rods a² a³ b² b³, which extend axially therefrom. Depending from the piston-rod a² is a yoke C, consisting of a transverse slideway carrying slide-blocks c c', and depending from the piston-rod b² is a yoke D, consisting of a slideway parallel with the yoke C and carrying slide-blocks d d'. The piston-rods a³ b³ connect with a single cross-

head E, from opposite sides of which depend vertical rods e e', the latter flanking the exterior sides of the cylinders A B. Said rods e e' at their lower ends respectively connect with yokes F G, which latter consist of transverse slideways that respectively carry the slide-blocks f f' and g g'. Each of the slide-blocks aforesaid has a shaft portion journaled therein, being indicated, respectively, by the reference characters c², c³, d², d³, f², f³; and g², g³. The several shaft portions interconnect by means of intermediate inclined arms in manner to form two parallel crank-shafts each composed of a plurality of double-fulcrum cranks, said crank-shafts each having opposite end gears, respectively, and the ends H' K' I' L', respectively, of such shafts being journaled in a fixed bearing h i h' i', respectively. From the end H' power is taken off.

In the formation of said crank-shafts the shaft portion f² connects with gear H and portion f³ with gear I. Similarly, portion g² connects with gear K and portion g³ with gear L. An inclined arm c⁴ connects the shaft portions f² c², the shaft portions f³ c³ being similarly connected by an inclined arm c⁵. Also the portion g² is connected with portion d² by an inclined arm d⁴, while a similar arm d⁵ connects the portions g³ and d³. M indicates a fixed central bearing, in which is journaled a shaft portion m, the latter connecting by opposite inclined arms m' m² with the portions c² and d², respectively, while N indicates another centrally-disposed fixed bearing, in which is journaled a shaft portion n, the latter connecting by opposite inclined arms n' n² with the portions c³ d³, respectively. Hence the gears H and K and shaft portion m are journaled in fixed alined bearings, while the shaft portions c², d², f², and g² rotate about the axjs thus provided, through the vertical reciprocating action of the piston-rods a² b² and rods e e' and the horizontal reciprocation of the slide-blocks c d. These instrumentalities being offset beneath the cylinders are balanced in their operation by the gears I L and shaft portion n.

The shafts H' K' I' L' may respectively carry gear-wheels, as indicated at H I K L, and said wheels may have teeth, as H² K² I² L², which may be of fibroid or other sound-deadening material, the teeth H² I² being in mesh and the teeth K² L² being in mesh to equalize the power communicated to turn the

crank-shafts from the piston-rods a^2 b^2 and rods e e' through the rotation of shaft portions c^3 , d^3 , f^3 , and g^3 , the latter being horizontally reciprocated by their slide-blocks in 5 the slideways during the vertical reciprocation of the yokes.

The piston-rods a^2 b^2 are expanded at their points of connection with the yokes C D, as also are the rods e e' in their connection with 10 the yokes F G, the purpose whereof is to distribute the vertical force exerted by the pistons equally over said yokes at both sides of the central vertical line thereof.

While the connection between each piston, 15 its piston-rod, and yoke may be of a rigid character, I have shown at O a universal ball-and-socket joint between each piston-rod and yoke, also providing opposite vertical guideways, as at o o' , for each yoke to 20 maintain the vertical line thereof in their reciprocating action. Where desired, anti-friction devices may be employed to facilitate the operation of the moving parts.

P indicates the combustion-chamber, having 25 the inlet-valve p and exhaust-valve p' , and having a passage p^2 , communicating with a port p^3 in the cylinder, located to introduce an exploding charge between the pistons a a' of cylinder A, these parts being 30 duplicated for cylinder B.

A fly-wheel, as R, is carried by the engine-shaft H', or two of said fly-wheels may be employed, if desired.

In Figs. 4, 5, and 6 I have illustrated my 35 improvements as applied to a four-cylinder engine, the characters S' S' S' S', respectively, indicating the four cylinders thereof. Each of said cylinders is provided with two oppositely-acting pistons, as s s' for cylinder S', 40 s^4 s^5 for cylinder S', and s^6 s^7 for cylinder S', the pistons for cylinder S' not appearing in the drawings. Piston s , the lower piston (not shown) in cylinder S', and pistons s^4 and s^6 have piston-rods s^8 , s^9 , s^{10} , and s^{11} , respectively, each connecting with a yoke or horizontal slideway, as T T' T' T', respectively. Similarly, piston s' , the upper piston (not shown) in cylinder S', and pistons s^5 and s^7 , respectively, have piston-rods s^{12} , a piston-rod (not shown) for the upper piston in cylinder S', and the piston-rods s^{14} s^{15} , of which the rod s^{12} and the rod that is not shown connect with a cross-head U and the rods s^{14} s^{15} connect with a parallel cross-head U'. The 55 cross-head U has the opposite depending rods u u' flanking the engine, and the cross-head U' has the opposite depending rods u^2 u^3 . Said rods u u' u^2 u^3 connect, respectively, with yokes or slideways U' U' U' U'. 60 The yokes are all arranged in parallelism, but alternate from opposite sides, so that while a central crank-shaft composed of crank portions V, connected by inclined arms v, is mounted to slide in all the slideways or links, al-

ternate yokes, as U' T T' U' similarly carry a corresponding flanking crank-shaft composed of shaft portions W, connected by inclined arms w and journaled in slide-blocks w', and the alternate yokes U' T' T' U' likewise carry at the opposite side of the central crank-shaft a flanking crank-shaft composed of shaft portions X, connected by inclined arms x and journaled in slide-blocks x'. 70

Each crank-shaft is provided with an intermediate shaft portion Y, that is journaled in a fixed bearing, as y, and said crank-shafts are also journaled in end bearings, as Y'. The central crank-shaft carries the engine-shaft, as Y', also the fly-wheel, as Y'. It is 80 obvious that two of said fly-wheels may be employed, if desired, to balance the engine at both sides, and it is also equally obvious that each of the crank-shafts may be used to communicate power for driving purposes. 85

In order to balance or unify the movements of the several crank-shafts, I may provide each of them with a pair of intermeshing gear or friction wheels, as y' y'', whose peripheral portions may be of fibroid or the like. 90

The operations of the pistons, piston-rods, yokes, and multifulcrum crank-shafts are identical with those of the corresponding parts in the two-cylinder engine previously described. 95 It will be observed, however, that in the four-cylinder engine the power-transmitting crank-shaft is located centrally beneath the engine instead of being offset therefrom, as with the two-cylinder engine. By extending the plan indicated with respect to a two-cylinder and four-cylinder engine it will be clear that the same principle can be applied to engines having a greater number of cylinders. 100

On account of the reciprocating movement in a true vertical line permitted the piston-rods through the mechanisms herein described the pistons may travel in their cylinders at their highest possible speed without 105 injury to the cylinder-walls. This is a feature of very great importance, since, as is well known in this art, high-speed engines employing the usual swaying piston-rod develop an amount of sidereal friction which involves lubricant troubles and sometimes results disastrously to the cylinder. Hence efficiency and durability are well served by my improvement, which thus constitutes an important step in advance in gas-engine 115 practice. 120

Having now described my invention, I declare that what I claim is—

1. In an internal-combustion engine, a number of vertical cylinders, two opposed pistons adapted to reciprocate in each cylinder, a number of crank-shafts each having plural cranks, a vertically-reciprocating piston-rod for each piston, and a number of vertically-movable yokes, deriving movement from 125 130

- said piston-rods, each yoke having two of the plural cranks.
2. In an internal-combustion engine, a number of vertical cylinders, two opposed pistons adapted to reciprocate in each cylinder, a number of crank-shafts each having plural cranks, a central fixed bearing for each shaft, a vertically-reciprocating piston-rod for each piston, a number of vertically-movable yokes, deriving movement from said piston-rods, said yokes each having two of the plural cranks, and blocks slidable horizontally in said yokes forming fulcra for said cranks.
3. In an internal-combustion engine, a number of vertical cylinders, two opposed pistons adapted to reciprocate in each cylinder, a number of crank-shafts carrying intermeshed gear-wheels, each shaft having plural cranks, a vertically-reciprocating piston-rod for each piston, a number of vertically-movable yokes each having two of the plural cranks, means communicating movement to said yokes from said piston-rods, and blocks slidable horizontally in said yokes forming fulcra for said crank-shafts.
4. In an internal-combustion engine, a number of vertical cylinders, two opposed pistons adapted to reciprocate in each cylinder, a number of crank-shafts carrying intermeshed gear-wheels, each shaft having plural cranks, a fixed central bearing for each shaft, a vertically-reciprocating piston-rod for each piston, a number of vertically-movable yokes each having two of the plural cranks, means communicating movement to said yokes from said piston-rods, and blocks slidable horizontally in said yokes forming fulcra for said cranks.
5. In an internal-combustion engine, a number of vertical cylinders, two opposed pistons adapted to reciprocate in each cylinder, a number of crank-shafts each having plural cranks, a vertically-reciprocating piston-rod for each piston, a number of vertically-movable yokes each having two of the plural cranks, and vertical guideways for said yokes.
6. In an internal-combustion engine, a number of vertical cylinders, two opposed pistons adapted to reciprocate in each cylinder, a number of crank-shafts each having plural cranks, a fixed central bearing for each shaft, a vertically-reciprocating piston-rod for each piston, a number of vertically-movable yokes each having two of the plural cranks, and vertical guideways for said yokes; together with blocks slidable horizontally in said yokes and forming fulcra for said cranks.
7. In an internal-combustion engine, a number of vertical cylinders, two opposed pistons in each cylinder, a piston-rod for each piston, a vertically-reciprocating yoke for each piston-rod, a cross-head for the upper piston-rods, vertically-reciprocating connections between said cross-heads and yokes, crank-shafts having plural cranks, slide-blocks capable of horizontal movement in said yokes and carrying said cranks, and opposite gear-wheels upon the crank-shaft; together with two flanking shafts having plural cranks journaled in slide-blocks carried by said yokes and equalizing gear-wheels upon said flanking shafts meshed with the gear-wheels upon the crank-shaft.
8. In an internal-combustion engine, a number of vertical cylinders, two opposed pistons in each cylinder, a piston-rod for each piston, a cross-head for each pair of upper piston-rods, a crank-shaft having plural cranks, a number of parallel yokes, some connecting with the lower piston-rods, vertically-reciprocating connections between said cross-heads and the other yokes, and gears upon said crank-shaft; together with two flanking shafts having equalizing gear-wheels meshing with the gears upon said crank-shaft, each of said flanking shafts having plural cranks, said yokes each carrying a crank of the crank-shaft and a crank of one of the flanking shafts.

Signed at New York this 24th day of August, 1905.

JEFFERSON TREEN.
